ARTICLE OF WEARING APPAREL AND
METHOD OF MAKING ITGustav Gastrich, Wyomissing, Pa., assignor to
Textile Machine Works, Wyomissing, Pa., a corporation of Pennsylvania

Application August 12, 1936, Serial No. 95,592

20 Claims. (Cl. 66—173)

My invention relates to knitted fabrics, and to a method of making them, and particularly to elastic areas of tubular form, as in the welts of stockings, or like portions of other garments.

In such art, it has been usual to form garter or band like portions in stockings and other garments or wearing apparel for the purpose of holding the fabric in position, as by enclosing a separate elastic garter in a folded welt, by sewing an elastic braid garter to, or topping it on, the top of a stocking, by knitting a welt portion of elastic yarn, and by other means.

Many of the former fabrics have been subject to one objection or another, such as binding with too great, or too little, force on the leg of the wearer, and locally concentrating the binding force of the elastic, as along a line about the leg, instead of over a wider area. The appearance, the cost, the comfort, the durability, and other features have also rendered the fabrics objectionable in many ways.

Another important objection to elastic welts or garters heretofore attached to, or carried by, the stockings, has resulted from the fact that the elastic band portions, in relaxed condition, have been of the same peripheral dimensions as the inelastic yarn stocking top, whereby, since the elastic fabric has greater stretch than the fabric of inelastic yarn, a tendency to tear the latter, or rupture its loops, has resulted from attempts to unduly extend the elastic.

Among the objects of this invention are to provide an elastic welt, or the like, of improved appearance, softer feel, freedom from cutting or binding along narrow lines, greater durability and better proportioned binding force, and that shall be simple and durable in construction, economical to manufacture and effective in its operation.

More in particular the invention contemplates the provision of a folded or double-layer welt or the like for a full-fashioned silk stocking, in which one layer is of inelastic yarn, such as silk, and the other entirely supports means for rendering it elastic, such as coursewise of walewise panels or sub areas of elastic yarn knitted into, and with, inelastic yarn, or by having such other layer entirely of elastic yarn, as of rubber covered with fibre, such as cotton or silk, or with other material.

Having a simple fold of inelastic yarn at its top edge from which an inelastic yarn margin extends downwardly on the elastic layer side, the welt, band or garter lies flat against the wearer's skin, precluding local binding as at the top edge,

and distributes its slight, but sufficient, binding effect substantially throughout its area.

The elastic layer is preferably on the inside of the welt next to the skin, and the outer, or inelastic layer is also preferably contracted or gathered, as in walewise folds or pleats, whereby to give free play to the inner layer for substantially greater expansion than it would otherwise have, to cause the outer layer to lie smooth on the leg, substantially free from its folds or pleats, and to improve the appearance of the stocking. Thus, in its position off the leg of the wearer, the welt presents an ornamental pleated effect, while, in service, it will be smooth or less pleated, depending upon the extent to which it is stretched. In any case, the elastic layer is obscured, by which fact, it may be produced more from the standpoints of durability, economy and effective service, and less from the standpoint of expensive decoration, than in the case of exposed elastics.

Another feature of importance, in one form of the invention, resides in the provision of margins of inelastic yarn along the selvage edges of a knitted blank otherwise constructed of, or including, elastic yarn, whereby to provide for effective, and usual, seaming between these edges; these margins or other inelastic areas, in one form, being joined to the elastic panels or areas by split seams.

An important phase of the invention resides in the article and the method of producing it whereby, a fabric having an area including elastic yarn has certain wales from which the loops are inclined oppositely.

A ribbed characteristic of the elastic layer renders it more elastic and provides a desirable gripping or holding feature relative to the skin of the wearer, when employed as an article of wearing apparel, such as a stocking.

By the above-outlined features, particularly of the pleated outer layer of inelastic yarn combined with the elastic inner layer, much greater stretch is provided at the jointure of the welt and the main leg portion, without danger of injury to the loops of the main leg portion, thus precluding runners and rendering the placing of a stocking on the wearer's leg a much simpler, faster, and more convenient operation safer to the stocking.

With these and other advantages incident to a utilization of the improvements, the invention comprises the parts and combinations thereof hereinafter set forth and claimed, with the understanding that the several necessary elements may be varied in construction, texture, re-

lation and other features without departing from the spirit and scope thereof.

In the drawings:

Figure 1 is a view, in perspective, taken from the front and with parts broken away, of a full-fashioned stocking embodying my invention;

Fig. 2 is a view, on a reduced scale, of the flat blank from which the stocking of Fig. 1 is constructed; the welt being folded with its inner layer showing;

Fig. 3 is a view, on a slightly larger scale, similar to the top portion of Fig. 2, showing the welt and upper leg portions of the invention in modified form;

Fig. 4 is a view taken along the line 4—4 of Fig. 3;

Fig. 5 is a view, similar to Fig. 3, of a further modified form of the invention;

Fig. 6 is a view taken along the line 6—6 of Fig. 5;

Fig. 7 is a detail view, on a greatly enlarged scale, of the loop structure in an area A of Fig. 1;

Fig. 8 is a view, similar to Fig. 7, of an area B of Fig. 5; and

Fig. 9 is an enlarged detail view taken substantially along the line 9—9 of Fig. 1.

Referring to Figs. 1 and 2, the stocking illustrated as one example of the invention, is of the full-fashioned type, comprising a welt W, a leg L and a foot F, of which the leg L and the foot F are not deemed necessary of detail description, since they are, or may be, constructed as in any full-fashioned stocking.

By also referring to Fig. 9, it is better seen that the welt W of Figs. 1 and 2 comprises an outer layer 10, and an inner layer 12 formed by a continuous knitting operation, in which the first few courses are of inelastic yarn to form a narrow margin 14 for topping onto the needles at the welt line M, after which, the elastic yarn of the layer 12, having the same number of loops to the course as the inelastic yarn, is knitted to a course N. Following course N a number of courses are knitted from inelastic yarn to form a margin 15 spacing the course N from the top or picot edge E of the stocking blank. Continued knitting from inelastic yarn forms the outer layer 10, the yarn of which may be further knitted for a few courses into the upper leg area, where it may be changed, or yarn of the same or different character, knitted by one carrier, or by a plurality of carriers to render the leg area of the ringless type.

Also, the welt W has selvage edge margins S, see also Fig. 7, of cotton, silk, or other fibrous or inelastic yarn, preferably the same as the remainder of the inelastic yarn of the welt, to permit the formation of an ordinary seam K. As shown in Fig. 1, seaming at the welt leaves the usual opening 16.

More in detail, the first course of the blank is a loose course of plain loops of inelastic yarn, to facilitate topping onto the needles at the welt line M. This course is followed by several courses of normal length plain loops of the same yarn to form the narrow margin or area 14, after which, the elastic yarns of the welt and the inelastic yarns of the selvage edges S of the welt are knitted to have the same number of loops to the course, as shown more in detail in Fig. 7. The selvage margins S are constructed of plain loops 17 of inelastic yarn joined to the elastic yarns 18 by split seams 19.

The elastic yarns 18 are knitted to have wales 75

of plain loops 21 joined by transferred stitches 22 to provide the elastic area with a ribbed or better gripping effect. As appears clearly in Fig. 7, the ribbed areas 21 have a coursewise width of two wales and the transferred loops 22 are taken from single wales one on each side of the given rib 21. Further, all the loops in the wales adjoining the ribs 21 are transferred, those in every other course being transferred to the right and those in alternate courses being transferred to the left so that single thread areas are produced between the ribs in which the threads incline alternately to the right and to the left with respect to the walewise direction. However, a given rib area 21 does not have a double loop thickness across its entire width along any one course, each course of a given rib area 21 having an inclined or transferred loop on one side at one course and an inclined or transferred loop on the other side in the next course.

In the above-described form, the inner elastic layer 12 of the welt is constituted substantially as a single elastic panel G, completely surrounded by inelastic yarn margins, as above set forth, thus protecting the elastic area at its ends and sides, and causing it to be supported entirely by the inner layer. The yarns are fed to the knitting mechanism so that, in drawing them off the needles, the elastic yarn contracts relative to the inelastic yarn, whereby, in its relaxed state, the inner layer 12 causes the outer layer 10 to assume a slightly contracted or gathered formation. Therefore, when the inner layer is stretched, as in placing the stocking on the leg of the wearer, the outer layer has much greater play than were it to be of normal peripheral dimensions, secured in this condition to the elastic layer such that stretching of the elastic layer would stretch the layer of inelastic yarn beyond the elastic limit which the layer has by reason of its loop formation.

As shown in Figs. 3 and 4, the inner layer 12a is provided with panels 24 of elastic yarn disposed in series about the welt Wa and joined to each other by walewise areas 25 of inelastic yarn, to which the panels may be joined by split seams; this arrangement reducing the amount of elastic yarn required, providing a different way of selecting the degree of stretch, lending variety of design, causing areas to alternately contact and to not contact, respectively, with the skin of the wearer, and having other benefits.

In the modification of Figs. 5, 6 and 8, a plurality of walewise-spaced elastic panels or bands 27 extend coursewise about the welt Wb, this structure offering further possibilities, differing from the forms of Figs. 1 and 3, in the selection and variety of elasticity and appearance.

Of course, the improvements specifically shown and described, by which I obtain the above results, can be changed and modified in various ways without departing from the scope of the invention herein disclosed and hereinafter claimed.

I claim:

1. A knitted garment comprising a multi-layer portion including an outer layer of inelastic yarn, and an inner layer embodying an area of inelastic yarn extending walewise while the garment is in use and alternate elastic and inelastic areas only the elastic areas of which positively contact the skin of the wearer.
2. A knitted fabric comprising a zone having

alternating areas each solely of elastic and inelastic thread and in which only the areas of elastic thread have walewise extending ribs.

3. A knitted garment comprising a zone having alternating areas each solely of elastic and inelastic thread, said areas of elastic thread having greater average thickness than those of inelastic thread and arranged to contact the person when in use with greater pressure.

4. A knitted garment comprising a two ply portion the inner ply of which includes a zone having alternating areas each solely of elastic and inelastic thread, said areas of elastic thread initially contracted in the coursewise direction to cause a gather in the outer ply and to provide relatively greater coursewise elasticity, said elastic thread areas being also of greater average thickness than those of inelastic thread and arranged to contact the person when in use with greater pressure.

5. A knitted fabric comprising a two ply portion the inner ply of which includes a zone having alternating areas each solely of elastic and inelastic thread, said areas of elastic thread having walewise ribs and coursewise spaces.

6. A flat knitted welt for a stocking having one or more sections knitted solely from elastic yarn arranged to contact the person of the wearer when in use and having walewise ribs separated by single thread areas.

7. A flat knitted welt for a stocking having one or more sections knitted to include elastic yarn arranged to contact the person of the wearer when in use and having walewise ribs separated by single thread areas in which the threads incline oppositely in successive courses.

8. A flat knitted welt for a stocking having one or more sections knitted solely from elastic yarn arranged to contact the person of the wearer when in use and having coursewise spaced ribs comprising two sets of loops, one set straight in the walewise direction and the other inclined to the walewise direction, said ribs separated by a relatively thin walewise zone.

9. A flat knitted welt for a stocking having one or more sections knitted solely from elastic yarn arranged to contact the person of the wearer when in use and having coursewise spaced ribs of overlapping straight and inclined loops, said ribs separated by single thread areas only one wale wide and having threads in adjoining courses inclined in opposite directions.

10. A flat knitted welt for a stocking having one or more sections knitted to include elastic yarn arranged to contact the person of the wearer when in use and having coursewise spaced ribs each two wales wide of overlapping inclined and straight loops, said inclined loops occurring in all the courses, some on one side and some on the other, but those on one side of a given rib occupying only alternate courses.

11. A flat knitted welt for a stocking having one or more sections knitted solely from elastic yarn arranged to contact the person of the wearer when in use and having coursewise spaced ribs each of plural wale width and having inclined loops extending from both sides, the inclined loops extending from one side of a rib lying in courses alternating with the courses of those extending from the other side of the rib.

12. A flat knitted welt for a stocking having one

or more sections knitted solely from elastic yarn arranged to contact the person of the wearer when in use and having coursewise spaced ribs each of plural wale width and having inclined loops extending from both sides, the inclined loops extending from one side of a given rib lying in courses alternating with those extending from the other side of the same rib, said ribs spaced by areas of single thread thickness and of single wale widths in which all the threads are inclined to the walewise direction but have alternately different inclinations.

13. The method of making a welt for a stocking comprising knitting courses partly of elastic and partly of inelastic yarns, joining the elastic yarn to the inelastic yarn by a split seam, transferring loops in alternate courses of certain wales to the wales at the right of said certain wales and transferring the remaining loops of said certain wales to the wales at their left.

14. The method of producing a welt for a stocking comprising knitting said welt partly of elastic and partly of inelastic yarns, transferring the loops in alternate courses in certain wales in areas of elastic yarn to the wales on the right of said certain wales and transferring the remaining loops of said certain wales to the wales at their left.

15. A stocking having a plain knit top section, said top section having consecutive courses of regular stitches of inelastic yarn, an immediately following course having a plurality of spaced transferred stitches and an immediately following series of courses providing a series of coursewise spaced ribs, said series of courses being knit of elastic yarn at least substantially throughout.

16. A flat knitted article having one or more sections knitted solely from elastic yarn arranged to contact the person of the wearer when in use and having coursewise spaced ribs comprising two sets of loops, one set plain and the other set transferred, said ribs separated by single thread areas.

17. Knit hosiery having an elastic zone integrally knit solely of elastic yarn and comprising a series of coursewise spaced rows of conventional lace stitches extending in a generally walewise direction, with intervening ribs thickened through the presence of the loops transferred in the formation of said stitches.

18. A knitted article having a zone entirely of elastic yarn and comprising a plurality of courses having transferred loops therein arranged in coursewise spaced rows and coursewise spaced ribs intersecting the courses substantially throughout the area having said transferred loops therein.

19. A flat knitted article having a ribless inelastic yarn area adjacent to a zone formed entirely of elastic yarn and having coursewise spaced ribs extending from one edge to an opposite edge of said zone, each rib having a width of more than one needle wale.

20. A knitted fabric having a zone entirely of elastic yarn, said zone having ribs extending substantially entirely across it in the walewise direction and each rib comprising a needle wale of plain loops and loop portions from an adjacent wale of loops.

GUSTAV GASTRICH.
